UNITED STATES PATENT OFFICE

2,102,762

REFRIGERATING APPARATUS

Otto M. Summers, Dayton, Ohio, assignor to General Motors Corporation, Dayton, Ohio, a corporation of Delaware

Application July 10, 1934, Serial No. 734,524

4 Claims. (Cl. 62—4)

This invention relates to refrigerating apparatus and more particularly to means for controlling the operation of refrigerating systems. This application is a continuation in part of my application Serial No. 145,950 filed November 3, 1926, which has matured into Patent No. 2,035,575 issued March 31, 1936.

Refrigerating systems are normally controlled by starting and stopping the circulation of refrigerant in the system according to certain high and low pressure and temperature limits. Heretofore, in adjusting these limits, a change in one of the limits would effect the other limit, even when not desired. This made the task of setting the proper limits of controlling an extremely difficult one.

It is an object of my invention to provide an improved refrigerating system controlled by starting and stopping the circulation of refrigerant according to predetermined high and low temperature and pressure limits, which system is provided with means for setting and adjusting each of the limits entirely independently of the other.

It is another object of my invention to construct a refrigerating system in such a way that the controller diaphragms are protected from pressure pulsations within the system. It is a further object of my invention to provide a refrigerating system which is controlled by the pressure or temperature differential between the high pressure portion of the system and the low or evaporating portion of the system.

Further objects and advantages of the present invention will be apparent from the following description, reference being had to the accompanying drawings, wherein a preferred form of the present invention is clearly shown.

In the drawings:

Fig. 1 is a front view partly in section of an improved controller for controlling the operation of the refrigerating system;

Fig. 2 is a view similar to Fig. 1, but showing certain elements of the controller in different positions;

Fig. 3 is a side view of the controller;

Fig. 4 is a diagrammatic view of a refrigerating system including the improved controller; and

Fig. 5 is a diagrammatic view of another form of refrigerating system including the improved controller.

The present invention is particularly adapted to refrigerating systems in which it is desirable to render a motor operative when a predetermined high temperature is present, and render the motor inoperative when a predetermined low temperature is present. Fig. 4 shows one manner of connecting the present controller in a refrigerating system. The system includes a compressor 86 which is driven by a motor 87. The

compressor 86 is adapted to withdraw refrigerant from an evaporator 88 through a pipe 89 and force the compressed refrigerant through a pipe 90 into a condenser 91, whence it passes by a pipe 92 to the evaporator 88. The chamber 28 of the controller 20 is connected by a pipe 93 with the low pressure pipe 89. When the motor 87 and compressor 86 are idle, the evaporator becomes warmer and the refrigerant within the evaporator 88, pipes 89 and 93 will increase in pressure and when such pressure attains a predetermined value, contact 74 will close with contact 80 to complete the electrical circuit to the motor 87. The operation of the compressor 86 will cause the pressure within the low pressure side of refrigerating system to decrease and when said pressure falls to a predetermined value, which value is computed in accordance with the temperature desired in the evaporator 88, the controller 20 will separate contact 74 from contact 80 to thus render the motor 87 inoperative.

In case the refrigerating system does not operate satisfactorily, as, for example, the refrigerant in the condenser 91 is not cooled as required, the excessive pressure within the high pressure side of the system will be transmitted to chamber 27 through the pipe 94, which pipe is connected on the high pressure side of the refrigerating system. When an excessive pressure is present within the system, the pressure within the chamber 27 will force the diaphragm 23 outwardly and rotate the lever 38, which lever 38 will operate through the pin 40 to rotate lever 43 in a counterclockwise direction, whereby contact 74 is separated from contact 80.

In systems in which there is present periodic pulsations such as those caused by the operation of a compressor and in which the diaphragm is subjected to these pulsations, said diaphragm is vibrated at a relatively high speed on each impulsion. This, in effect, will cause the diaphragm to fracture quickly. In the present invention this objection has been overcome by preventing the vibration of said diaphragm. The pipes 93 and 94 have a relatively small cross-sectional area and are of such length so as to provide a resistance to the flow of refrigerant to such an extent that the pulsations are not transmitted to the chambers 27 and 28. By providing this resistance, the pressure values do not change rapidly within said chambers and said chambers are responsive only to the mean pressure within the respective high pressure and low pressure sides of the refrigerating system. By subjecting said diaphragms only to the mean pressure within the system, no pulsation is present within said chambers and, therefore, the diaphragms 23 and 24 will not vibrate.

In Fig. 5 there is shown a direct expansion type of refrigerating system embodying my invention.

tion. This system includes a compressor 110 for compressing the refrigerant and for forwarding the compressed refrigerant through a conduit 111 to a condenser 112 where the compressed refrigerant is liquefied and forwarded through a supply conduit 113 to an expansion valve 114. The expansion valve 114 is located within an insulated enclosure 115 and controls the supply of liquid refrigerant to an evaporating means 116 located in heat exchange relation with the interior of the enclosure. The evaporating means 116 absorbs heat from the interior of the enclosure and evaporates the liquid refrigerant, which is returned through the return conduit 117 to the compressor. The compressor 110 is driven by an electric motor 119 which is started and stopped by my improved controller 20, which is located in series with the electric motor circuit 121 which supplies electric energy to the electric motor 119. The chamber 28 of the controller 20 is connected by a pipe 193 with a thermostatic bulb 194 which is located in heat exchange relation with the evaporating means 116 and which is, therefore, responsive to the temperature as well as the pressure of the evaporating means 116. When the motor 119 and the compressor 110 are idle, the evaporator becomes warmer and the volatile refrigerant within the thermostatic bulb 194 expands, thus increasing the pressure within the tubing 193 and the chamber 28 and when such pressure attains a predetermined value, the contact 74 will close with contact 80 to complete the electrical circuit to the motor 119. The operation of the compressor 110 will evaporate liquid refrigerant within the evaporating means to decrease the temperature of the evaporating means and the interior of the insulated enclosure 115. This will also reduce the temperature of the thermostatic bulb 194, thus causing the pressure within the tubing 193 and the chamber 28 to be reduced, and when said pressure falls to a predetermined value, which value is computed in accordance with the temperature desired in the evaporator 116, the controller 20 will separate the contact 74 from the contact 80 to thus stop the electric motor 119.

In case the refrigerating system does not operate satisfactorily, as, for example, when the refrigerant in the condenser 112 is not cooled as required, the excessive pressure within the high pressure side of the system will be transmitted to the chamber through the pipe 195 which preferably has a relatively small cross sectional area so as to provide a resistance to the flow of refrigerant to such an extent that the pulsations within the system are not transmitted to the chamber 27. This pipe 195 is connected to the conduit 111 which is in open communication with the condenser 112. When an excessive pressure is present within the system, the pressure within the chamber 27 will force the diaphragm 23 outwardly and rotate the lever 38, which lever 38 will operate through the pin 46 to rotate the lever 43 in a counterclockwise direction whereby contact 74 is separated from the contact 80. Thus, the controller in reality is controlled by both the pressure within the condenser and the temperature and pressure of the evaporating means.

Referring to Figs. 1 to 4, the controller 20 includes a base 21 to which is secured an upright 22. Adjacent the lower portion and on opposite sides thereof, there are provided diaphragms 23 and 24 which are spaced from the upright 22 by gaskets 25 and 26 to provide chambers 27 and

28, respectively, between said diaphragm 23 and upright 22, and between upright 22 and diaphragm 24. Plates 29 and 30 are also disposed on opposite sides of the upright 22 and are arranged coextensive with the diaphragms 23 and 24. The diaphragms, gaskets and plates are suitably secured to the upright 22 by screws 32. A disc 33 is disposed between the plate 29 and the diaphragm 23, and a disc 34 is disposed between the diaphragm 24 and plate 30. Ears 36 are carried by the plate 29, which ears support the fulcrum pin 37 upon which is pivotally mounted a lever 38. One end of lever 38 is arranged to be engaged by the disc 33 and the other end of said lever engages a pin 40 which extends through the upright 22. The plate 30 carries ears 41, which ears support a fulcrum pin 42 which in turn carries an operating member or lever 43. The lower end of said lever 43 is arranged to engage with pin 40. A pin 44 pivotally connects lever 43 with ears 45, which ears are secured to the disc 34.

The plate 29 is tapped at 46 to receive a coupling which is connected with a source of pressure, and a passage 47 connects said tapped portion with the chamber 27, said passage including a drilled hole within the plate 29 and diaphragm 23 and a cut-away portion in the gasket 25. The plate 30 is tapped at 48 and is provided with a passage 49 similar to that of 47, which passage connects with chamber 28. Pressure within the chamber 27 causes the disc 33 to move outwardly and rotate the lever 38 in a counterclockwise direction, which will cause the lever 43, by means of the pin 40, to rotate in a counterclockwise direction. Pressure within the chamber 28 will cause the disc 34 to move outwardly and rotate the lever 43 in a clockwise direction.

Adjacent the upper portion of the upright 22 there is provided a sleeve 50 which extends through said upright and is suitably secured thereto. A plunger 51 extends through one end of said sleeve and the extreme end thereof is provided with a cone-shaped recess 52. A screw-threaded bushing 53 is connected with the opposite end of the sleeve 50 and a spring 54 is located within the bushing 53 and a stop 55, and normally tends to force the plunger 51 to the right. Stop 55 engages the end wall of a sleeve 50 and thus limits the movement of said plunger 51.

A stem 57 is located above the pin 51 and extends through the upright 22. Stem 57 is provided with a stop 58 to limit the movement of said stem toward the left. A nut 59 is provided on said stem 57 and a spring 60 is interposed between said nut and the upright 22 and normally tends to move the stem toward the left. Stem 57 carries a pin 61 which is slidably movable within a slot 62 formed in lever 43. Ears 64 are provided by the upright 22 and extend parallel to the plunger 51 and the stem 57. A fulcrum pin 65 is carried by the ears 64, which in turn carries an actuating mechanism including parallel-spaced arms 66 which support a roller 67. A spring 68 is wound about the pin 65 and normally tends to rotate said roller 67 in a clockwise direction.

A switch lever 70 is bodily or translatively carried by the lever 43, by a pin 71. The lower arm of lever 70 is connected with a link 72 by pin 73, which link is connected to a pivotally-mounted contact 74 by a pin 75. Contact 74 is pivotally supported at 76 upon an insulating block 77. The contact 74 is provided with a stop 75

78 to prevent the counterclockwise movement of said contact 74 beyond a certain limit. Contact 74 is arranged to engage with contact 80 carried by the insulating block 77. The upper end of lever 70 is provided with a cam 82 having camming surfaces 83 and 84 either of which is arranged to cooperate with the roller 67. When the roller 67 engages the camming surface 84, the lever 70 will be in the position shown in Fig. 10, the stop 79 of the pivoted contact 74 limiting the movement of the lever 70. When the lever 43 is moving outwardly, carrying with it the lever 70, the camming surface 84 will move over the roller 67 and after the apex, formed by the 15 camming surfaces 83 and 84, has moved beyond the roller, the roller 67 will engage the camming surface 83. When this occurs, the spring 68 will force the roller 67 downwardly, which in turn will quickly rotate the lever 70 in a clockwise 20 direction. When the lever 43 moves in the opposite direction, lever 70 will be moved, so that the camming surface 83 will be moved beyond the roller and when said roller engages surface 84 the lever 70 will quickly rotate about pivot 25 71 in a counterclockwise direction. Fig. 1 shows the position of lever 43 while said lever is moving toward the right and the lever 70 is still in the position in which the roller 67 maintains contact 74 separated from contact 80. A still 30 further movement of the lever 43 to the right is necessary before camming surface 83 engages roller 67. Fig. 2 shows the position of lever 43 while said lever is moving toward the left, the camming surface 83 being still in engagement 35 with the roller 67. A further movement of the lever 43 to the left is necessary before surface 84 engages said roller. It will be noted that when the lever 43 is moving toward the right, the fulcrum pin 71 of lever 70 is farther to the right 40 when the apex of cam 82 engages roller 67, than when the apex engages roller 67 while the lever 43 is moving toward the left. This is the result of the lever 70 being pivotally and translatively carried by the lever 43 since the lever 70 is at 45 a different angle while said lever 43 is moving in one direction than the angle of lever 70 when lever 43 moves in the opposite direction. The movement of the lever 43 to the right is resisted by the spring 60 and the movement of the lever 50 43 to the left is resisted by the spring 54, there being a projection 85 on the lever 43 which is adapted to engage plunger 51 to compress the spring 54. The arrangement is such that the stop 55 on the plunger 51 will engage the end 55 wall of sleeve 50 before the lever 43 has moved to such a position in which the camming surface 84 has moved beyond the roller 67, and the spring 54 is ineffective. The tension of the 60 spring 60 can be adjusted and in this manner said spring individually controls the amount of pressure necessary for closing the switch contacts 74 and 80. As the pressure within the chamber 28 decreases, the lever 43 will move to the left and while the camming surface 83 is still 65 engaging the roller 67, the stop 58 upon the stem 57 will engage the upright 22 and thus render the spring ineffective as regards to lever 43. While the camming surface 83 is still engaging roller 67, projection 85 on lever 43 will engage the plunger 51. Thus the spring 54 will 70 resist the movement of the lever 43 to the left

and the tension of this spring can be adjusted by the nut 53. Since spring 60 is now ineffective, the tension of spring 54 alone controls the pressure at which the contacts 74 and 80 are separated. Thus it is apparent from the foregoing 5 description that there is provided high and low pressure adjustments which are entirely independent of one another, whereby the pressure at which the contacts are closed can be adjusted entirely independently of the pressure at which 10 the contacts are opened and, likewise, the pressure at which the contacts are opened can be adjusted independently of the pressure at which the contacts are closed. 15

While the form of embodiment of the invention as herein disclosed, constitutes a preferred form, it is to be understood that other forms might be adopted, all coming within the scope of the claims which follow. 20

What is claimed is as follows:

1. Refrigerating apparatus comprising a closed refrigerating system having means for circulating condensing and evaporating refrigerant, means for automatically controlling the circulation of refrigerant including means for controlling the starting and stopping of the circulation of refrigerant according to predetermined temperature limits and separate means for separately adjusting the starting of the circulation, and separate means for adjusting the stopping of the circulation, said starting and stopping adjusting means being entirely independent of each other and being independently adjustable, each of said separate means acting effectively solely during a period when the other separate means is not acting effectively. 30 35

2. Refrigerating apparatus comprising a closed refrigerating system having means for circulating condensing and evaporating refrigerant, means for automatically controlling the circulation of refrigerant including means for controlling the starting and stopping of the circulation of refrigerant according to predetermined temperature limits, and separate means for separately adjusting the starting and stopping of the circulation 40 45 entirely independently of and without affecting the critical points controlled by each other.

3. Refrigerating apparatus comprising a closed refrigerating system having means for circulating condensing and evaporating refrigerant, means for automatically controlling the circulation of refrigerant including means for controlling the starting and stopping of circulation of refrigerant according to predetermined temperature limits, and means for adjusting the stopping of the circulation without affecting the critical point or any adjustment which determines the starting of the circulation. 50 55

4. Refrigerating apparatus comprising a closed refrigerating system having means for circulating, condensing, and evaporating refrigerant, means for automatically controlling the circulation of refrigerant including a plurality of separately confined spring means acting independently for separately controlling the starting and stopping of circulation of refrigerant according to predetermined temperature limits, each of said independently acting spring means acting effectively solely during a period when the other independently confined spring means is not acting effectively. 60 65 70

OTTO M. SUMMERS.
